UNITED STATES PATENT OFFICE.

JOHN WARD GRUMMON, OF EAST ORANGE, NEW JERSEY, ASSIGNOR TO THE INDIA RUBBER COMB COMPANY, OF NEW YORK, N. Y.

ROSETTE FOR HARNESS.

SPECIFICATION forming part of Letters Patent No. 377,750, dated February 14, 1888.

Application filed November 15, 1887. Serial No. 255,184. (No model.)

To all whom it may concern:

Be it known that I, JOHN WARD GRUMMON, of East Orange, Essex county, New Jersey, have invented an Improved Illuminated Rosette 5 for Harness and Analogous Purposes, of which the following is a specification.

The object of my invention is to provide an illuminated rosette for harness and analogous purposes wherein the letters, symbols, &c., forming the illumination can be changed when desired by a simple adjustment of the parts composing the rosette.

The invention consists in a shell or frame having an opening and screw-threads, combined with a back plate or disk having a corresponding screw-thread adapted to fit the threads in the shell, a removable plate or disk having a suitable symbol or symbols produced upon it adapted to be held within said shell 15 or frame by said back plate, and means for holding said symbol-plate on the back plate to prevent its turning when the parts are being put together, as will be more fully hereinafter set forth.

Reference is to be had to the accompanying drawings, forming part of this specification, in which—

Figure 1 is a face view of an illuminated rosette constructed according to my invention. 30 Fig. 2 is a reverse view of the symbol-plate; and Fig. 3 is a central cross-section on the line *c c*, Fig. 1.

In the accompanying drawings, *A* represents a frame or shell having a suitably-shaped opening, *a*, overhung by a lip or flange, *i*. The frame or shell *A* may have any suitable outline and be constructed of any suitable material; but I prefer to use india-rubber. The frame *A* is provided with screw-threads *b*, 35 preferably on its inner wall, as shown in Fig. 3.

B is a back plate or disk provided with screw-threads *d*, adapted to fit the threads *b*. The back plate, *B*, is preferably arranged to fit within the frame *A*, as shown in Fig. 3.

D is a plate or disk adapted to fit within the frame, as shown, and it has produced upon it a letter or monogram, *e*, or other suitable symbols, which, when the disk *D* is in position in the frame *A*, may be seen through the opening *a*. The back plate, *B*, serves to hold the

symbol-disk *D* within the frame *A*. A glass, *f*, may be placed over the symbol-disk *D* to protect its face.

To place a symbol-disk *D* in the rosette, the parts are first separated. The glass *f* is then placed in the frame *A* against the inwardly-projecting lip or flange, *i*. A symbol-disk *D* is then placed in the frame *A* and the back plate, *B*, screwed into position. The parts will now be held firmly together. 60

By means of a loop, *g*, carried by the back plate, *B*, the rosette may be held on a bridle or other part of a harness. The letter or symbol is designed to stand in the same line with the loop *g*, so as to be in vertical position with 65 reference to the harness. To hold the symbol-disk in its proper position with reference to the loop *g*, I provide the inner or reverse side of the disk *D* with two or more recesses, *h*, into which pins or other projections, *j*, from the 70 plate *B* project. In the drawings the pins *j* are shown to be the inner ends of the loop *g*; but, if preferred, the pins *j* may be separate from the loop *g* and be suitably secured to the plate *B*; or the pins *j* could be on the symbol-disk *D* and the recesses *h* be in the back plate, *B*. 75

The pins *j* when on the plate *B* could enter notches in the edge of the disk *D*, if desired. The loop *g* for supporting the rosette may be replaced by one or more buttons or other projections, which will answer the same purpose. When the loop *g* is used, a suitable strap on 80 the bridle or other part of the harness may pass through it to support the rosette.

With rosettes as above constructed the symbol may be changed at any time by merely changing the disk *D*, the other parts of the rosette remaining as before.

Having now described my invention, what I claim is—

1. The combination, with the shell *A*, having opening *a*, lip *i*, and thread *b*, with the removable back *B*, and means, substantially as described, for holding the back on the shell, of the detachable symbol-disk *D*, and with pins 95 *j*, for holding said disk in position in the rosette, substantially as described.

2. The open shell *A*, removable back *B*, having pins *j*, and means for holding the back on the shell, in combination with the detachable 100

symbol-disk D, having recesses *h*, adapted to receive the pins *j* to hold the disk in position, substantially as described.

3. The back plate, B, having loop *g* and pins *j*, symbol-disk D, having recesses *h*, adapted to receive the pins *j* to hold the symbol in line with the loop *g*, in combination with the open shell A, having lip *i*, and means, substantially as described, for holding the shell A on the back B, substantially as specified.

4. The combination of the open shell A, having lip *i*, back B, having pins *j* and threads *b* *d*, for holding the parts A B together, detachable symbol-disk D, having recesses *h*, and glass *f* in front of the disk D, substantially as described.

J. WARD GRUMMON.
